Primary Examiner—James Gandy*Assistant Examiner*—Stacia Sinuik*Attorney, Agent, or Firm*—Taylor & Associates, P.C.**[57] CLAIM**

The ornamental design for a cargo barrier for a vehicle interior, as shown and described.

DESCRIPTION

FIG. 1 is a perspective view of a cargo barrier for a vehicle interior showing my new design;

FIG. 2 is a front view thereof;

FIG. 3 is a side view thereof, the opposing side view being substantially the same;

FIG. 4 is a top view thereof;

FIG. 5 is a rear view thereof;

FIG. 6 is a bottom view thereof; and,

FIG. 7 is a side view thereof, with the cargo barrier in a folded position.
